SAFETY RAZOR BLADE

Ralph E. Thompson, Brookline, Mass., assignor
to Gillette Safety Razor Company, Boston,
Mass., a Corporation of Delaware

Original application April 25, 1929, Serial No.
358,114. Divided and this application August
18, 1932. Serial No. 629,321

7 Claims. (Cl. 30—12)

5 My invention relates to safety razors in which a thin, flexible and elastic blade is removably secured in a holder comprising a guard member adapted to support the blade adjacent to its longitudinal cutting edges and a transversely-curved cap member provided on opposite sides with parallel straight edges which engage the blade adjacent to the longitudinal edges of the latter and flex it transversely on the guard member as a fulcrum during the process of 10 clamping the blade in the holder, so that, when the razor is ready for use, the blade is maintained in a transversely curved condition and subjected to a pronounced stress, particularly at its 15 longitudinal edge portions.

15 The Gillette razor exemplifies the type of razor which is described above, and the standard thickness of the flexible blade used in this razor is 0.006 inch. It is to blades of substantially this 20 order of flexibility, and to such blades only, that the present invention relates. For convenience that type of razor will be referred to in this specification and in the appended claims as the "Gillette type", which term will imply the 25 entire description contained in the preceding paragraph.

30 In the use of such a razor, satisfactory operation requires very accurate positioning of the blade edge with respect to the guard, and consequently it is extremely desirable that the parts which engage and flex the blade should retain, 35 permanently, the precise shapes and dimensions imparted to them when manufactured. This is particularly true of the longitudinal straight edges of the blade-clamping cap, on which the alignment and amount of exposure of the blade edges depend, but inasmuch as these 40 cap edges are necessarily made thin, in order to enable the cutting edge of the blade to reach the skin when the razor is held at the proper shaving angle, they are very easily deformed, particularly at the cap corners, to such an extent as seriously to impair the efficiency of the razor.

45 For example, the mere dropping of the razor, or of the cap alone, has frequently resulted in bending over a corner of the cap to an extent sufficient, when the clamping pressure is applied to the blade, to produce an uneven edge exposure or even to crack or break off a portion of 50 the blade itself. Such a result may occur even when the bending of the cap corner is so slight that it is not likely to be noticed by the user, this being due to the fact that the pressure thereby applied to the blade tends to flex it 55 locally in a different direction from that in

which it has already been flexed by the cap as a whole, and according to a familiar geometrical principle the blade can not be so flexed, even slightly, without subjecting it to a greatly increased stress. In such a case the user invariably considers the unsatisfactory operation of his razor to be due to a defective blade, and either continues to use the defective holder and to find fault with the blades, or else discards the 60 razor in favor of one of another make. 65

To meet the difficulty above explained I have devised an improvement which is applicable to any razor of the construction hereinbefore described and may be embodied therein without making any change except in the outline of the 70 blade itself, my improved blade being given such a contour that even if the blade-clamping cap is bent at one or more of its corners, the positioning of the blade edge under the flexing action of the holder will not be affected thereby, 75 nor will the blade be broken or cracked. In consequence, it becomes possible not only to obtain efficient service from razors using such blades, even if the cap corners become bent, but also to restore to satisfactory use a very 80 large number of such razors which have been discarded or are now giving unsatisfactory service.

85 My invention will be best understood and appreciated from the following description of a preferred embodiment thereof selected for purposes of illustration and shown in the accompanying drawing, in which—

Fig. 1 is a view in perspective of one form of 90 razor containing my improved blade;

Fig. 2 is a view in perspective of the cap and blade shown in Fig. 1, in position for assembling;

Fig. 3 is a sectional view illustrating in partially assembled relation the parts shown in 95 Fig. 1;

Fig. 4 is a view in perspective, on an enlarged scale, showing a portion of the cap with the blade applied thereto.

100 The blade-holding parts of the razor illustrated in Figs. 1, 2 and 3 of the drawing are of standard construction and comprise a guard 12 provided with guard teeth 13 on each of its longitudinal edges and with parallel shoulders 14 constituting fulcrums on which the flexible blade is flexed transversely when clamped in the holder, a transversely-curved cap 15 having blade-positioning studs 16 and a threaded center pin 17 projecting from its inner face and adapted to pass respectively through perforations in the guard member 12, a hollow handle 110

18 secured at one end to the guard member at the center of the latter, and a nut 19 adapted to turn freely in the handle 18 and having its inner end internally threaded to engage the 5 pin 17, whereby the parts are clamped together. As in razors of this type, the internal apertures 23 provide edges arranged to engage the studs 16 thus holding the blade positively against rotation or angular displacement and 10 with its sharpened edges properly located in the razor for shaving.

The longitudinal edges 10 of the cap 15 overhang and are parallel with the shoulders 14, and are located above channels 21 formed in 15 the guard member 12 in position to underlie the cutting edges of the blade, so that when the blade is clamped in the holder its cutting edges are adjustably positioned and held over the channels 21, as described in U. S. Letters Patent 20 No. 1,328,024, dated January 13, 1920.

The blade 22, shown best in Fig. 2, is or may be like the standard blade commonly used in razors of the type above described, in that it is of substantially uniform thickness transversely 25 flexible, is sharpened on its parallel longitudinal edges to provide two cutting edges, has perforations 23 and 24 to receive the studs 16 and center pin 17 respectively, and is long enough at its center to overhang the ends of the cap 15, the latter feature being desirable not only to facilitate the removal of the blade from the cap but also to provide enough metal between the 30 end perforations 23 and the ends of the blade to prevent cracking of the latter along its center line.

In contrast to the standard blade previously referred to, however, my blade 22 is provided at each of its four corner portions with a reentrant recess 25 which bounds the corresponding end 40 of the adjacent cutting edge and is so proportioned that when the blade is clamped in the holder these recesses span the respective corners of the cap 15 and provide clearance spaces of sufficient size to receive said corners if bent 45 over or otherwise distorted to any extent which is likely to result from accidental damage. Consequently my blade while being flexed transversely by the cap 15 is engaged only by those portions of the straight edges 10 of the cap 50 which lie between the corresponding recesses 25, and can not be broken or cracked by a damaged cap corner either while being flexed or when flexed in final position in the holder.

Referring to Fig. 4, it will be noted that the 55 reentrant recesses 25 are each bounded internally by substantial fillets or inwardly-curved portions, the effect of which is to prevent excessive concentration of stress at these points when the blade is flexed and thereby avoid breakage 60 on account of such stresses.

The blade of my invention is described and claimed in combination with a safety razor of well-known construction in my co-pending application, Serial No. 358,114, filed April 25, 1929, 65 of which the present application is a division.

Having thus described my invention, what I claim as new and desire to secure by Letters Patent of the United States is:—

1. As a new article of manufacture, an elastic, transversely-flexible safety razor blade adapted for use in existing Gillette-type safety razors, said blade having unsharpened ends, being of uniform thickness, requiring external support on both sides for its cutting edge and being internally apertured to provide edges ar-

ranged to engage positioning and clamping means and hold the blade against angular displacement, and being also provided with re-entrant recesses including a rounded portion at the inner angles thereof, located at the corner portions of the blade respectively and each extending both longitudinally and transversely of the blade to such an extent as to span the adjacent corner of the blade-clamping cap when assembled therewith, and to provide a clearance space of sufficient area to receive a cap corner if bent, whereby said blade while being flexed or when clamped cannot be subjected to pressure by a bent cap corner and danger of breaking said blade or distorting its cutting edge is eliminated.

2. As a new article of manufacture, a razor blade of the Gillette type internally apertured to provide edges arranged to engage positioning means and hold the blade against angular displacement, and requiring external support on both sides for its cutting edge and of substantially uniform thickness and flexibility between its internal apertures and the cutting edges, said blade having reentrant recesses located in 100 its corner portions providing clearance spaces of sufficient area to prevent clamping pressure by the corners of a blade holder, each recess having its inner corner curved in concave contour to avoid excessive stress concentration adjacent to the perimeter of the recess.

3. As a new article of manufacture, an elastic, transversely-flexible razor blade adapted for use in existing Gillette type safety razors, said blade having unsharpened ends, being of uniform thickness and so thin as to require external support on both sides thereof for substantially its full length to give rigidity to its cutting edge, and being internally apertured to provide edges arranged to engage positioning and clamping 110 means and hold the blade against angular displacement, and being also provided with re-entrant recesses located at its corner portions respectively and each extending both longitudinally and transversely of the blade to such an extent as to span the adjacent corner of the blade-clamping cap when assembled therewith, and provide a clearance space of sufficient area to receive a cap corner if bent, whereby said blade while being flexed or when clamped is 115 relieved of the possibility of pressure from a bent cap corner, each of said recesses having an inner concave fillet shaped to prevent excessive stress concentration thereat.

4. As a new article of manufacture, an elastic transversely-flexible razor blade adapted for use in existing Gillette type safety razors, said blade being internally apertured to provide edges arranged to engage positioning means and hold the blade against angular displacement, and being of substantially uniform thickness and so thin as to require external support on both sides thereof for substantially its full length to give rigidity to its cutting edge, and being also provided with reentrant recesses located at its corner portions respectively and each extending both longitudinally and transversely of the blade to such an extent as to span the adjacent corners of the blade-clamping cap when assembled therewith and provide a clearance space of sufficient area to receive a cap corner if bent, whereby said blade while being flexed or when clamped is relieved of the possibility of pressure from a bent cap corner.

5. A flexible blade for use in safety razors of 150

- the type in which the blade is positioned between cap and guard members and is maintained transversely bent thereby when the parts are clamped together, said blade being of uniform thickness and so thin as to require external support on both sides for its cutting edge, being internally apertured to provide edges arranged to engage positioning means and hold the blade against angular displacement, and being cut away at each of its corners at a cutting edge thereof to such an extent as to provide clearance spaces of sufficient areas to receive the cap corners and thereby prevent clamping pressure by said corners. 80
- 15 6. A flexible blade for use in safety razors of the type in which the blade is positioned between cap and guard members and is maintained transversely bent thereby when the parts are clamped together, said blade being of uniform thickness and so thin as to require external support on both sides for its cutting edge, having unsharpened ends and being internally apertured to provide edges arranged to engage positioning means and hold the blade against angular displacement, said blade having portions cut away at the ends 85
- 20 turned to provide edges arranged to engage positioning means and hold the blade against angular displacement, said blade being provided with cutaway portions at its corners at the cutting edges thereof to such an extent as to span the adjacent corners of the blade-clamping cap when assembled therewith thereby providing clearance spaces of sufficient area to each receive a cap corner if bent whereby said blade while being flexed or when clamped is relieved of the possibility of pressure from a bent cap corner. 90
